UNITED STATES PATENT OFFICE.

LEE A. MILLER, OF MILWAUKEE, WISCONSIN, ASSIGNOR TO SAMUEL B. FULLER, OF WATERTOWN, WISCONSIN; MARY B. FULLER ADMINISTRATRIX OF SAID SAMUEL B. FULLER, DECEASED.

TENSION FOR SEWING-MACHINES.

SPECIFICATION forming part of Letters Patent No. 657,351, dated September 4, 1900.

Application filed January 29, 1900. Serial No. 8,094. (No model.)

To all whom it may concern:

Be it known that I, LEE A. MILLER, a citizen of the United States, and a resident of Milwaukee, in the county of Milwaukee and State 5 of Wisconsin, have invented certain new and useful Improvements in Sewing-Machines; and I do hereby declare that the following is a full, clear, and exact description thereof.

My invention consists in certain peculiarities of construction and combination of parts constituting a sewing-machine spool-thread tension mechanism; and said invention has for its object to improve the details of like mechanism set forth in my application for 15 patent, Serial No. 731,589, filed September 25, 1899, the improvements being hereinafter particularly described with reference to the accompanying drawings, and subsequently claimed.

Figure 1 of the drawings represents a partly sectional plan view of a portion of a sewing-machine arm and my improved spool-thread tension mechanism in connection therewith; Fig. 2, a view of the assemblage, partly in 25 vertical longitudinal section, the spool-thread pincer, constituting part of said assemblage, being broken at intervals thereof; Fig. 3, a side elevation of the aforesaid assemblage, and Fig. 4 a detail partly-sectional view indicated by line 4 4 in the first figure.

Referring by letter to the drawings, A indicates a portion of the arm of a sewing-machine head provided with an upper elongate socket-bracket B, that constitutes a seat for 35 a spool-thread pincer C, this pincer being a strip of spring metal bent to form meeting jaws b, having their extremities clear of said bracket adjacent to a groove c therein, and as one of the features of my improvements 40 one of the jaws is bent at a right angle to form a flange d in front of the other of said jaws, this flange being by preference approximately half-round. The jaw-flange is provided with a central horizontal open slot 45 e, intercepting an eye f, that portion of said flange above its eye being preferably less wide than the remainder and slightly offset from the same. The eye of the jaw-flange serves as a guide for spool-thread, and said

flange constitutes a guard for preventing automatic displacement of said thread from the tension device. 50

One side of the socket portion of the sewing-machine arm-bracket B is provided with an angular opening engaged by a corresponding angular nut D, that opposes the adjacent side of the spool-thread pincer back of its jaws, and that end of the nut next said pincer is preferably flanged, as herein shown. A screw E, engaging socket-bracket B, the 60 spool-thread pincer, and nut D, is provided with a shoulder g, that bears against said pincer opposite said nut; and adjustment of the screw regulates the tension of the pincer-jaws upon the spool-thread. 65

The groove c in the socket-bracket B is sufficiently wide to permit of the jaws b of the screw-controlled tension device yielding in opposite directions to knots or other irregularities of spool-thread, and from the foregoing it will be understood that as there is equal pressure at all times of the screw and nut on opposite sides of said tension device proper alignment of this device in said bracket is preserved, this being another important feature of my improvements. 70 75

Having thus described my invention, what I claim as new, and desire to secure by Letters Patent, is—

1. In a sewing-machine, the arm thereof 80 provided with an upper elongate forwardly-grooved socket-bracket, a bent spring-metal plate seated in the bracket to constitute a spool-thread pincer having the jaws thereof expansible in the bracket-groove, one of these 85 jaws terminating in a flange that crossing the front of the other jaw is provided with an eye intercepted by an open slot, and means for regulating tension of the pincer.

2. In a sewing-machine, the arm thereof 90 provided with an upper elongate forwardly-grooved socket-bracket, a bent spring-metal plate seated in the bracket and constituting a spool-thread pincer having the jaws thereof expansible in the bracket-groove, an angular nut loose in a corresponding angular opening in one side of said bracket back of the pincer-jaws, and a bracket, pincer and 95

nut engaging screw having a shoulder opposing said pincer opposite said nut.

3. In a sewing-machine, the arm thereof provided with an upper elongate forwardly-grooved socket-bracket, a bent spring-metal plate seated in the bracket to constitute a spool-thread pincer having the jaws thereof expandable in the bracket-groove, one of these jaws terminating in a flange that crossing the front of the other jaw is provided with an eye intercepted by an open slot, an angular nut loose in a corresponding angular opening

in one side of said bracket back of the pincer-jaws, and a bracket, pincer and nut engaging screw having a shoulder opposing said pincer opposite said nut. 15

In testimony that I claim the foregoing I have hereunto set my hand, at Milwaukee, in the county of Milwaukee and State of Wisconsin, in the presence of two witnesses.

LEE A. MILLER.
